UNITED STATES PATENT OFFICE.

THOMAS K. NISHIOKA, OF PORTLAND, OREGON.

DISPENSING APPARATUS.

1,301,301.

Specification of Letters Patent. Patented Apr. 22, 1919.

Application filed July 23, 1915. Serial No. 41,601.

To all whom it may concern:

Be it known that I, THOMAS K. NISHIOKA, a subject of the Emperor of Japan, and a resident of Portland, county of Multnomah 5 and State of Oregon, have invented a new and useful Improvement in Dispensing Apparatus, of which the following is a specification.

The object of this invention is to provide 10 an efficient dispensing or vending device, especially adapted for dispensing cigars, or cigarettes and matches, and further so arranged that the delivery of either one of the former will simultaneously deliver a match.

15 It is further my special object to make my device of the humidor type, and also to arrange the construction and operation of my device on very simple plans, so that the device may be easily and inexpensively 20 built.

The means by which I attain my object are fully illustrated in the accompanying drawings, in which:

Figure 1 is a front elevation of the device;

Fig. 2 is a vertical section taken approximately on the line 2—2 of Figs. 1 and 4;

Fig. 3 is a vertical section taken on the line 3—3 of Figs. 1 and 4; and

30 Fig. 4 is a vertical section taken on the line 4—4 of Figs. 2 and 3.

The receptacle comprises a case having a base *a*, front *b*, top *c*, side-walls *d*, and back *e*. Inside the case at the sides are partitions *f* and the back *g*. The partitions *f* are provided with the cut-out portions *f'*. An inclined floor *h* extends between the partitions *f*, the rear partition *g* and the front *b*, and the compartment thus formed above 40 the floor *h* is adapted to hold a plurality of cigars *i*. In the rear of the cigar-holding compartment, (see Fig. 3) is a sponge chamber *j* adapted to hold the moist sponge *k*, which keeps the humidity in the compartment to the desired degree. A hinged cover *c'*, provides a means of access to the cigar compartment.

50 Journaled between the end-walls of the cigar compartment is a transverse rock shaft *l* upon which is fixed the resilient rockable gate *m*. This gate restrains all except the forward one of the lower layer of cigars from rolling down said inclined floor; the forward cigar being, however, permitted to 55 drop on the pan *n* carried by the extremities

of a pair of rockable arms *5*, pivoting on a transverse pivot-pin *o*.

In the lower portion of the case are the sliding drawers *p* and *q*, the former adapted to serve as a receptacle for matches and the latter for cigarettes. Said drawers are provided on their bottoms with tongues *p'* and *q'* respectively which slide in guide grooves in the base *a* of the case. On the rear ends of the drawers *p* and *q* are hooks *p²* and *q²* 60 respectively. Flat springs *r* fixed on a bar *r'* bear against the rear of each drawer, and normally tend to push the drawers out as shown in the broken lines of Fig. 2, to expose their contents.

70 On a transverse pivot pin *r²* are pivoted the hook levers *t* and *u*, their rear ends extending through slots in the partition *g* and said rear ends bear in the slotted lower ends of the plunger rods *v* and *w*. Flat springs 75 *t'* and *u'* normally tend to throw the forward ends of the hook levers *t*, *u* down. When the drawers *p*, *q* are shut, the hooks *p²*, *q²* will be engaged with the hook levers *t*, *u*, and thus prevent the springs *t'*, *u'* from 80 acting to push the drawers out. The two plunger rods *v* and *w* extend vertically downward in the space between the partition *g* and back *e*. Brackets *g'* form bearings for the lower ends of the plunger 85 rods, and compression coil springs *g²*, normally hold said rods in their up position. Pins *v'* in the upper part of both rods slide on the fixed guide bars *v²*, and serve the two-fold purpose of limiting the upward movement 90 of the plunger rods and at the same time preventing said rods from rotating.

An arm *x* is pivoted at *x'* (see Fig. 4) to one of the side-walls *d* and its other end is pivoted on a pin *x²* in the plunger rod *w*. 95 Said arm *x* overlies the rear end of the hook lever *t* so that when the plunger rod *w* is depressed, both hook levers *t* and *u* will be lifted and both drawers *p* and *q* will simultaneously be released and opened.

100 In the front *b* of the case is hinged, on an axis *b⁵*, (see Figs. 3 and 4) a delivery door *b'* and a bracket *b²* fixed on the outer face of the front of the case, supports the door when dropped in a horizontal position. The inner 105 face of this door is recessed as indicated by *b³* in Fig. 3, so as to form a pocket for the cigar which is delivered thereon. On one end of said door is a spring arm *b⁴*, against which strikes the finger *6* of the pan *n*, when 110

the latter is lifted by the rocking of the arms 5, and in so doing throw the door b' open in advance of the lifting of the cigar to the level of the door.

5 Pivoted on the transverse pivot-pin o (see Figs 2 and 4) is a bell-crank o'. One arm of said bell-crank is slotted as indicated by o². A pin v³ carried by the plunger rod v bears in said slot. The other arm of the bell-crank o' is pivoted to an operating arm m' fixed on the rock shaft l of the gate m. In this way, when the rod v is pushed down, the gate will be rocked counter clockwise (see Figs. 2 and 3). The rockable arms 5 10 are also pivoted on the pivot-pin o, and one of said arms is provided with an operating end 5' located slightly below the pin v³ on the push rod v, and in the path of motion thereof (see Figs. 2 and 4). Stops 7 fixed 15 on the side-walls limit the degree of rotation of the rockable arms 5.

20 The general operation of the device is as follows: Having reference to Fig. 3, it is to be noted that one of the cigars has dropped down onto the pan n, the others being held back by the gate m. When the plunger rod v is depressed, the bell-crank o' will be rocked so as to swing the gate m in a counter clockwise direction having reference to Fig. 3. This action causes said gate 25 to move the remaining cigars out of the way while the cigar on the pan n is being delivered.

30 In coöperation with said movement of the

gate, the arms 5 will be rocked clockwise so as to elevate the pan n, and the cigar retained thereon. When the delivery door b' has been thrown as shown in broken lines in Fig. 2, the cigar will roll off the pan n onto said door. Simultaneously with the delivery of the cigar, the match drawer p will be sprung open, and the user will then have a cigar and matches at his disposal.

35 When the devices are returned to their normal position the next cigar will drop 40 onto the pan n and be ready for delivery.

45 If the smoker wishes to smoke a cigarette, he will depress the plunger rod w. In this case, both drawers p and q will be sprung open, thereby permitting the operator to 50 select a cigarette and a match. For the purpose of convenience, a match striker plate 8 is fixed on the front of the box.

I claim:

55 In a dispensing apparatus comprising a case and inclined floor therein, a pit at the lower end of the latter and a door located above such pit, the combination of a rockable arm extending to said pit and carrying a pan normally resting in the latter, said door being provided with an inwardly projecting arm lying in the path of motion of one edge of said pan and whereby the door is opened upon the lifting of the latter, and means including a depressible rod for lifting said arm.

60 THOMAS K. NISHIOKA.

Copies of this patent may be obtained for five cents each, by addressing the "Commissioner of Patents, Washington, D. C."
